UNITED STATES PATENT OFFICE.

HENRY R. JOHNSON, OF NEWELL, SOUTH DAKOTA.

AUTOMOBILE-EXTRACTOR.

1,209,588.

Specification of Letters Patent. Patented Dec. 19, 1916.

Application filed March 14, 1916. Serial No. 84,149.

To all whom it may concern:

Be it known that I, HENRY R. JOHNSON, a citizen of the United States, residing at Newell, in the county of Butte and State of South Dakota, have invented new and useful Improvements in Automobile-Extractors, of which the following is a specification.

This invention relates to automobile extractors, or devices whereby an automobile is enabled to extricate itself from a mired position by the power of the engine thereon, the object of the present invention being to provide in connection with a cable and drum therefor mounted on the frame of the machine, means for throwing said drum into and out of engagement with the engine shaft, whereby the drum may be operated independently of the wheel driving mechanism of the machine thus enabling the full power of the engine to be utilized for winding the cable on the drum when the free end of the cable is secured to a tree, post or other anchoring device at a distance from the machine.

With the above and other objects in view, the invention consists in the novel construction, combination and arrangement of parts, as herein described, illustrated and claimed.

In the accompanying drawings:—Figure 1 is a fragmentary plan view of an automobile, the same being broken away to show the mechanism of this invention in its applied relation to the machine. Fig. 2 is a front view of the same. Fig. 3 is a fragmentary vertical longitudinal section of the same. Fig. 4 is a fragmentary vertical section showing the pawl and ratchet connection between the drum and its shaft.

Referring to the drawings 1 designates a drum and 2 a cable wound thereon and preferably having one end fastened to the drum. The drum 1 is normally loose on a shaft 3 extending centrally and longitudinally therefrom and journaled in hangers 4 and 5 adjacent to the ends thereof, said hangers being secured in fixed relation to the frame bars 6 of the machine.

Adjacent to one end of the drum 1, the shaft 3 has fast thereon a bevel gear 7 which meshes with and is driven by another bevel gear 8 fast on a short shaft 9 extending longitudinally of the machine frame and journaled in a hanger 10 secured to the frame. Fast on the same shaft 9 is a sprocket wheel 11 from which a chain 12

extends around another sprocket wheel 13 normally loose on the engine shaft 14. The sprocket wheel 13 is provided with a clutch face 15 adapted to be engaged by a clutch 16 keyed to the engine shaft as indicated at 17 but slideable to a limited extent longitudinally thereof. The clutch 16 is shifted by means of a lever 18, said lever being provided at one end with a fork 19 which engages the clutch 16 and being fulcrumed between its ends at 20 on a bracket 21 fastened to the machine frame. To the other end of the lever 18 is attached an operating rod 22 which extends rearwardly in order that it may be operated by the driver of the machine for the purpose of shifting the clutch 16 into and out of engagement with the clutch face 15 of the sprocket wheel 13 thereby locking the sprocket wheel 13 to the engine shaft 14 and causing the engine to revolve the drum 1 and wind the cable 2 thereon. At one end the drum 1 carries a pawl 23 which engages a ratchet wheel 24 fast on the shaft 3. By moving the pawl 23 out of engagement with the ratchet wheel 24, the cable 2 may be unwound rapidly from the drum and the free end thereof carried to a distant point and fastened to a suitable anchor. The pawl 23 is then returned to its engagement with the ratchet wheel 24 so that thereafter when the shaft 3 is driven, rotary motion will be imparted to the drum 1.

In operation, when an automobile or similar vehicle equipped with the present invention becomes mired so that it cannot extricate itself by the traction of its own driving wheels, the operator dismounts from the machine, unwinds the cable 2 and secures the free end thereof to a suitable anchoring device at any desired distance in front of the machine. He then throws the dog 23 into engagement with the ratchet wheel 24 and returns to his seat in the machine. He then speeds up the engine and shifts the clutch 16 into engagement with the clutch face of the ratchet wheel 13. Thereupon the power of the engine shaft is transmitted to the drum 1 and the cable 2 is wound slowly thereon, the result being that the machine is pulled from its mired position and advanced toward the point where the free end of the cable 2 has been anchored. This operation may be repeated and continued until the wheels of the automobile rest on solid ground after which the

machine may be operated under its own power.

The mechanism above described is mostly concealed, the drum 1 being preferably located just below the radiator indicated at 25.

Having thus described my invention, I claim:—

The combination with the frame and engine of a motor vehicle, of a rotary drum, 10 a flexible cable wound thereon, a shaft on which said drum is normally loose, means for connecting said drum to said shaft and disconnecting the same therefrom, a sprocket wheel normally loose on the engine shaft, a

clutch keyed to and slideable upon the engine shaft and movable into and out of engagement with said sprocket wheel, clutch operating means, a countershaft extending at right angles to the drum shaft and geared thereto, a sprocket wheel fast on said countershaft, and a chain extending around said sprocket wheels.

In testimony whereof I affix my signature in presence of two witnesses.

HENRY R. JOHNSON.
